FRANKLIN E. ARNDT, OF GALION, OHIO.

SEALING MEANS FOR VAULTS.

1,074,402.

Specification of Letters Patent. Patented Sept. 30, 1913.

Application filed December 24, 1912. Serial No. 738,403.

To all whom it may concern:

Be it known that I, FRANKLIN E. ARNDT, a citizen of the United States, residing at Galion, in the county of Crawford and State 5 of Ohio, have invented certain new and useful Improvements in Sealing Means for Vaults; and I do hereby declare the following to be a full, clear, and exact description of the invention, such as will enable others 10 skilled in the art to which it appertains to make and use the same.

This invention relates to vaults and particularly to burial vaults, the object of the invention being to provide a vault of this 15 character of comparatively simple and economical construction and particularly with a simple and secure joint between its side and end walls.

With this object in view, the invention 20 consists in the improved construction, arrangement and combination of the parts of a device of the character specified, which will be hereinafter fully described, and afterward specifically claimed.

25 In order that the construction and operation thereof may be readily comprehended, I will now proceed to fully describe my invention in connection with the accompanying drawing, which illustrates an approved 30 embodiment thereof, and which drawing represents a vertical sectional view on a plane extending longitudinally through the vault, the middle portion being broken out to shorten the figure.

35 Referring to this drawing, the body of the vault comprises a tubular member 5, a fixed closure or rear wall 6 and a front door frame 7. These several members may be made from any suitable material, but preferably from one of the baser metals, and they may be cast or forged, as preferred. The tubular member 5 is provided with apertures 8 adjacent to both ends, while the end members 6 and 7 are each provided with 40 laterally extending flanges 9 and 10, the latter forming the periphery of each end member, while the flanges 9 are spaced apart from the flanges 10 sufficiently to receive the respective ends of the member 5 and allow 45 considerable space around said ends. The

flanges 10 are curved inward, so as to form a seat 11 into which the member 5 is fitted, so as to support said member 5 in such relation that said space is divided by the end portions of the member 5. The inwardly 55 curved portions of the flanges also constrict or choke the entrances of the grooves between said flanges, for a purpose which will hereinafter be apparent. Into these spaces is placed plastic material 12 which will harden and secure the elements 5, 6 and 7 rigidly in unison. This material may consist of sulfur, cement, lead, or other suitable material. When the material 12 is placed in the peripheral grooves between the flanges 9 60 and 10, it is worked into the apertures 8, so as to form a locking bar or bolt 13 through said apertures, and it will be seen that the inwardly curved portions of the flanges 10 65 coact with the bolts 13 for preventing disengagement of the members 5, 6 and 7. It is also obvious that the material 12 entirely prevents the entrance or escape of air or moisture around the edges of the member 5. The end member or frame 7 is provided 70 with inwardly converging door seats 14 and 15 while a movable door 17 is provided with inclined side surfaces fitting therein, secured by locking bolts 21 operated by the volute cam 26. Any other suitable form of frame, 75 door and securing mechanism may be used.

It will be seen that I have provided a device of this character which is fully capable of attaining the foregoing objects, and in a thoroughly practical and efficient manner. 85

I do not limit my invention to the exact details of construction, combination and arrangements of parts, as herewith illustrated and described, but my invention may only be limited by a reasonable interpretation of the 90 claim.

I claim:—

In a vault comprising side walls, an end closure having its outer edges curved inward into substantially semi-elliptic form with 95 the extreme edge resting upon the side walls at a distance from their ends, said end walls being provided with perforations in that portion inclosed by the curved inward edges of the end closure, an inwardly projecting 100

flange on the inside of the closure at distance from its edge parallel with and spaced away from the side walls, and a plastic sealing ring, filling the space between the curved 5 edges and flange of the closure and forming retaining bars in the perforations of the side walls.

In testimony whereof I have signed my name to this specification in the presence of two subscribing witnesses.

FRANKLIN E. ARNDT.
